DESIGN FOR A CIGARETTE HOLDER OR SIMILAR ARTICLE OF MANUFACTURE

Louis J. Robertson, New York, N. Y.

Application April 17, 1939, Serial No. 84,357

Term of patent 3½ years

To all whom it may concern:

Be it known that I, Louis J. Robertson, a citizen of the United States and resident of New York, county of New York, State of New York, have invented a new, original, and ornamental Design for a Cigarette Holder or Similar Article of Manufacture, of which the following is a specification, reference being had to the accompanying drawing, forming a part thereof.

I claim:

The ornamental design for a cigarette holder or similar article of manufacture, as shown.

LOUIS J. ROBERTSON.
